ROTARY BUFFING TOOL

Harold F. Wood, 67 N. Brainard Ave., La Grange, Ill.
Filed July 24, 1962, Ser. No. 211,995
7 Claims. (Cl. 15—97)

This invention relates generally to buffing tools and more particularly to buffing tools arranged for hand-held operation.

Rotary buffers for use around the home commonly comprise a hand-held power tool, a rubber disc adapted to be rotated about its center and a lamb's wool bonnet adapted to be secured over the rubber disc. In the use of buffers of this type the rotational axis is held approximately perpendicular to the work surface; and as a result, the fibers of the wool are drawn in circular paths about the axis of rotation. Objectionable "cobwebbing" is frequently produced in the polished surface because of this circularity in the paths traversed by the buffing fibers. Wheel-type arrangements have also been devised in which the thick edge of the wheel is adapted to provide the buffing action. While these latter arrangements situate the rotational axis parallel to the work surface, thereby drawing the buffing fibers in straight paths and eliminating the tendency to produce "cobwebbing," wheel-type buffers have heretofore been conceived of as bulky, heavy appliances suitable for use in the shop or factory but not amenable to either home use or portable applications.

Therefore, an important object of the present invention is to provide a light-weight, inexpensive and portable buffing appliance of the wheel-type.

A more general object of the present invention is to provide a new and improved wheel-type buffing appliance.

Another object of the invention is to provide a novel buffing member.

Still another object of the invention is to provide a detachable and disposable buffing member.

Yet another object of the invention is to provide a novel holder for a band-type buffing member.

These and other objects and features of the invention will become more apparent from a reading of the following descriptions.

An appliance in accord with the invention comprises a power tool including a chuck; holder means for a flexible buffing member, including an arbor adapted to be gripped by the chuck and finger elements endwise attached to a frame extending radially outwardly from the arbor, the finger elements extending away from the arbor parallel thereto; and a buffing member including a pliant, tensilely strong band having an endless portion and a plurality of link portions flexibly connected to the endless portion inwardly thereof, each of the link portions being looped detachably to receive one of the finger elements whereby rotation of the finger elements drives the endless portion through the link portions, the endless portion drawing tension in the link portions upon rotation.

In order that the principle of the invention may be readily understood, a single embodiment thereof adapted to incorporate a hand-held, electric drill as the motive means, but to which the application is not to be restricted, is shown in the accompanying drawing wherein:

FIG. 1 is a perspective view of a buffing appliance constructed in accordance with the invention and incorporating a hand-held, electric drill as the motive means, the appliance further incorporating a band-type buffing member shown expanded under the influence of centrifugal force in use;

FIG. 2 is an enlarged, end elevational view taken substantially along the line 2—2 of FIG. 1, the buffing member being shown in its relaxed state in solid outline and in its extended state in broken outline;

2

FIG. 3 is an enlarged view taken substantially along the line 3—3 of FIG. 1;

FIG. 4 is a reduced scale, end elevational view in partial cross-section of the buffing appliance of FIG. 1 with the power tool removed, showing lateral deformation of the buffing member upon contact with a work surface in use; and

FIG. 5 is an enlarged perspective view of the free end of a finger element of the holder, showing in detail one of the retaining elements.

Referring now in detail to the drawing, specifically to FIG. 1, a buffing appliance indicated generally by the numeral 10 will be seen to include a portable power tool 12, a holder device or spider frame 14 and a buffing member 16. The power tool 12 comprises an electric motor, not shown, which is connected to a suitable source of electric current by means of a cable 18 and which is operated by a trigger 20. The output shaft of the electric motor is coupled to a chuck 22 in accordance with conventional practice.

The holder device 14 comprises an arbor 24 which is adapted to be received and gripped by the chuck 22 of the portable power tool 12. Crossarms 26 are mounted to one end of the arbor 24, and a finger element 28 is affixed to each of the crossarms 26 to extend away from the arbor 24 parallel thereto. With reference to FIG. 3, the arbor 24 is seen to be fashioned with a threaded end portion 30, and the crossarms 26 are seen to be mounted between two nuts 32 and 34. The finger elements 28, on the other hand, are provided with threaded and reduced diameter end portions 36 which are passed through holes 38 fashioned in the crossarms 26. The reduction in diameter of the end portions defines shoulders 40 which abut the confronting faces of the crossarms to arrest movement of the finger elements in one direction. To complete the fastening of the finger elements, nuts 42 are turned over the threaded end portions 36, and lock washers 44 are advantageously disposed between the nuts 42 and the crossarms 26.

As will be recognized, the crossarms 26 can be fashioned as a welded or stamped unit as well as in the form of the separate parts described hereinabove. Similarly, other forms of joining the crossarms to the arbor and the finger elements to the crossarms may be employed. Furthermore, while it is to be noted that four finger elements are disclosed in the drawing, other numbers of the finger elements may also be employed. In any event, it is advantageous to position the finger elements 28 at equal radial spacings from the axis defined by the arbor 24 and at equal angular spacings from each other.

The buffing member 16 is defined by a pliant, tensilely strong band of material provided with a textured outer region which defines the buffing surface. Materials which provide the desired velvety or fuzzy surface include buff leather, muslin and felt. However, a napped fabric is most desirable because it combines high tensile strength with economy and good buffing properties. The buffing member 16 specifically comprises an endless portion 46 which is adapted for rapid rotation whereby to form a radially resilient cylinder under the influence of centrifugal force. The buffing member 16 includes additionally a number of link portions 48 flexibly and integrally connected to the endless portion 46 inwardly thereof. The link portions 48 are spaced at equal intervals along the length of the endless portion 46 and are shaped as loops. Buffing member 16 may be readily affixed to the holder device 14 by simply slipping the finger elements 28 into the loops or sleeves defined by the link portions 48. In one specific embodiment, the buffing member 16 has been fashioned from a continuous length of material wherein the endless portion and the link portions are defined by

appropriately disposed stiches 50 as shown in FIG. 2.

Upon assembly of the buffing member 16 with the holder device 14 and upon rotation of the holder device by means of the portable power tool 12, the centrifugal force developed on the endless portion 46 draws tension into the link portions 48; and in accordance with the invention, as disclosed hereinabove, the loop-type link portions and the endless portion of the buffing member are securely fastened together. It has been found that this arrangement prevents relative slippage of the components of the buffing member whereby to preclude jerky movement of the endless portion over a work surface.

For convenience in assembly and disassembly (as for replacement), the link portions 48 are adapted to receive the finger elements 28 loosely; and in order to prevent undesirable oscillation of the buffing member along the longitudinal axis of the finger elements, the pliant band from which the buffing member 16 is fashioned is selected to possess a width substantially equal to the length of the finger elements whereupon retaining elements 52 are mounted on the free ends of the finger elements to hold the buffing member in place. The retaining elements 52 may be fabricated as abbreviated arms in accordance with the showing in the drawing, or they may be fabricated as circular discs. In any event, the size of the retaining elements is selected so that the looped and sleeve-like link portions 48 may be readily slipped thereover. Furthermore, it is advantageous to dispose the retaining elements 52 so that they reside substantially totally within a cylinder defined by the outermost edge portions of said finger elements, extending radially inwardly from the finger elements as is best shown in FIG. 1. One convenient manner of affixing the retaining elements is shown in FIG. 5. There, the end of the finger element 28 is provided with a reduced diameter terminus 54 which is passed through a hole 56 fashioned in the retaining element. Thereafter, the emerging part of the terminus is riveted over to form a head holding the retaining element in place.

Having thus described one construction of the invention, it is important now to state how the illustrated embodiment operates. With the holder device 14 assembled to the power tool 12, the chuck 22 gripping the arbor 24, and with the buffing member 16 detachably assembled to the holder device, the link portions 48 receiving the finger elements 28, the buffing member 16 will take the suspended condition indicated in solid outline in FIG. 2 when the power tool is inoperative. Upon energization of the electric motor of the power tool, as by a depression of the trigger 20, the holder device 14 will be rotated and the finger elements 28 will be correspondingly driven through a circular path. Centrifugal force will thereupon cause the endless portion 46 to expand into a generally cylindrical shape as shown in broken outline in FIG. 2. The amount of centrifugal force developed is, of course, proportional to the speed of rotation and the weight of material used in making the buffing member 16. However, the speed of a conventional 1/4-inch portable electric drill and the weight of commercially available napped fabrics combine to develop adequate centrifugal force and concomitant resilient pressure in the endless portion 46 to perform the conventional polishing tasks in and about the home. The resilient pressure which is thus developed is also great enough to make it practically impossible to force the finger elements 28 close enough to the surface being buffed for the surface to be struck and damaged.

With reference to FIG. 4, it will be seen that the cylinder defined by the rotating buffing member is radially deformable upon pressuring engagement with a work surface 58 whereby to establish surface rather than mere line contact with the work. It will also be seen in FIG. 4 that the resilient pressure afforded by the centrifugal force makes it very difficult to press the rotating finger elements 28 into proximity with the work surface. As pointed out hereinabove, the retaining elements 52 are situated on the finger elements substantially totally within a circle

defined by the outermost edge portions thereof; and it will now become clear that the purpose of so situating the retaining elements is to prevent their colliding with the work surface in use of the buffing appliance.

The specific example herein shown and described is to be considered as being primarily illustrative. Various changes in structure and arrangement will, no doubt, occur to those skilled in the art; and these changes are to be understood as forming a part of this invention insofar as they fall within the spirit and scope of the appended claims.

The invention is claimed as follows:

1. An appliance for use in buffing and polishing operations and the like comprising: power tool means including a rotatable chuck; holder means for a flexible work member, including an arbor detachably gripped by said chuck, frame means extending radially outwardly from said arbor and finger elements endwise attached to said frame means extending away from said arbor parallel thereto in radially spaced relationship therewith; and a work member including a pliant, tensilely strong band having an endless portion provided with an integral, textured outer region which defines a work element, said endless portion being adapted for rapid rotation whereby to form a radially resilient cylinder, said tensilely strong band further having a plurality of pliant link portions flexibly connected to said endless portion inwardly thereof, said link portions receiving said finger elements, said endless portion drawing tension in said link portions upon rotation of said finger elements through a circular path, said endless portion and said link portions having sufficient flexibility to hang limply and substantially without rigidity when at rest whereby said band is shaped solely by centrifugal forces upon rotation in order to define a soft cushion capable of conforming readily to abrupt contours of the surface being worked.

2. An appliance for use in buffing and polishing operations and the like comprising: power tool means including a rotatable chuck; holder means for a flexible work member, including an arbor detachably gripped by said chuck, frame means extending radially outwardly from said arbor, finger elements endwise attached to said frame means extending away from said arbor parallel thereto in radially spaced relationship therewith, and a retaining element on the free end of each of said finger elements; and a work member including a pliant, tensilely strong band having an endless portion provided with an integral, textured outer region which defines a work element, said endless portion being adapted for rapid rotation whereby to form a radially resilient cylinder, said tensilely strong band further having a plurality of pliant link portions flexibly connected to said endless portion inwardly thereof, said link portions receiving said finger elements, said endless portion drawing tension in said link portions upon rotation of said finger elements through a circular path, said endless portion and said link portions having sufficient flexibility to hang limply and substantially without rigidity when at rest whereby said band is shaped solely by centrifugal forces upon rotation in order to define a soft cushion capable of conforming readily to abrupt contours of the surface being worked.

3. An appliance for use in buffing and polishing operations and the like comprising: power tool means including a rotatable chuck; holder means for a flexible work member, including an arbor detachably gripped by said chuck, frame means extending radially outwardly from said arbor, finger elements endwise attached to said frame means extending away from said arbor parallel thereto in radially spaced relationship therewith, and a retaining element on the free end of each of said finger elements, said retaining elements residing substantially totally within a cylinder defined by the outermost edge portions of said finger elements, said retaining elements extending radially inwardly from said finger elements; and a work member including a pliant, tensilely strong band having an endless portion provided with an integral, textured outer region

which defines a work element, said endless portion being adapted for rapid rotation whereby to form a radially resilient cylinder, said tensilely strong band further having a plurality of pliant link portions flexibly connected to said endless portion inwardly thereof, said link portions receiving said finger elements, said endless portion drawing tension in said link portions upon rotation of said finger elements through a circular path, said endless portion and said link portions having sufficient flexibility to hang limply and substantially without rigidity when at rest whereby said band is shaped solely by centrifugal force upon rotation in order to define a soft cushion capable of conforming readily to abrupt contours of the surface being worked.

4. A device for use in buffing and polishing operations and the like comprising a pliant, tensilely strong band having an endless portion and textured surface means integral with said endless portion and disposed exteriorly thereto to define a work element, said endless portion being adapted for rapid rotation whereby to form a radially resilient cylinder capable of deforming upon pressuring engagement with a surface to be worked, said tensilely strong band further having a plurality of pliant link portions flexibly connected to said endless portion inwardly thereof, each of said link portions being looped away from its point of connection with said endless portion to receive loosely and detachably a support member operable through a circular path for rotating said endless portion by means of said link portions, said endless portion drawing tension in said link portions upon rotation, said endless portion and said link portions having sufficient flexibility to hang limply and substantially without rigidity when at rest whereby said band is shaped solely by centrifugal force upon rotation in order to define a soft cushion capable of conforming readily to abrupt contours of the surface being worked.

5. A device according to claim 4 wherein said link portions are integrally connected to said endless portion.

6. A device according to claim 4 wherein said textured surface means is a napped surface.
7. An appliance for use in buffing and polishing operations and the like comprising holder means for a flexible work member, including a rotatable arbor adapted drivingly to be coupled to a power tool device, frame means extending radially outwardly from said arbor, elongated cantilevered finger elements endwise attached to said frame means extending away from arbor parallel thereto in radially spaced relationship therewith, and a work member including a pliant, tensilely strong band having an endless portion adapted for rapid rotation whereby to form a radially resilient cylinder, textured surface means integral with said endless portion and disposed exteriorly thereto to define a work element, and a plurality of pliant sleeve-like link portions flexibly connected to said endless portion inwardly thereof, said link portions telescopingly receiving said finger elements, said endless portion drawing tension in said link portions upon rotation of said finger elements through a circular path, said endless portion and said link portions having sufficient flexibility to hang limply and substantially without rigidity when at rest whereby said band is shaped solely by centrifugal force upon rotation in order to define a soft cushion capable of conforming readily to abrupt contours of the surface being worked.
